PRESSURE CONTROLLED THROTTLE VALVE

William A. Henry, Littleton, Colo.

Application June 25, 1934, Serial No. 732,269

7 Claims. (Cl. 236—26)

This invention relates to improvements in pressure controlled throttle valves.

In the operation of steam generating plants of the type employing forced draft, it is desirable to control the speed of the fan which is used for controlling the draft in accordance with the steam pressure within the boiler so that when the pressure within the boiler is low or decreasing, the speed of the fan will be high, thereby producing sufficient draft to secure maximum combustion and similarly when the pressure has attained the maximum value, the speed of the fan must be reduced so as to retard the combustion, but in no case must the fan be stopped entirely.

It is the object of this invention to produce a throttle valve that can be introduced in the steam supply pipe running from the boiler to a steam turbine of the type employed for operating a fan in connection with a forced draft system. The throttle valve is so constructed that the amount of steam that is permitted to flow will be varied inversely in accordance with the pressure in the steam boiler.

The above and other objects that may become apparent as this description proceeds are attained by means of a construction and an arrangement of parts that will now be described in detail, and for this purpose reference will be had to the accompanying drawing in which the preferred embodiment of the invention has been illustrated, and in which:

Fig. 1 is a side elevation of my improved steam controlled throttle valve, parts being broken away so as to better disclose the construction;

Fig. 2 is a section taken on line 2—2, Fig. 1, and shows the position of the parts when the valve occupies its maximum open position;

Fig. 3 is a side elevation partly in section showing the position of the parts when the valve is closed; and

Fig. 4 is a diagrammatic representation showing the valve in the position it occupies between the boiler and the steam turbine.

In the drawing reference numeral 5 designates a steam boiler and reference numeral 6 a steam turbine which is connected by means of a shaft 7 to a suitable fan which has been designated by reference numeral 8. The turbine is connected to the boiler by means of a steam pipe 9 and located in the pipe between the boiler and the turbine is my improved valve which has been designated by reference numeral 10. The construction of the pressure controlled valve has been shown in Figs. 1, 2 and 3 from which it will

be seen that it consists of a body member 11 that has a cylindrical opening 12 extending inwardly from one end thereof. The upper end of the body member is closed by an end wall 13 which is provided with a threaded opening 14 into which one end of the pipe 9 extends in the manner shown. Surrounding the lower end of member 11 is a flange 15 that is provided with two threaded openings 16. A plate 17 of the same outside diameter as the flange 15 is located beneath the latter and is held in place by means of the rods 18 and the nuts 19. The plate 17 has an opening 20 that is somewhat smaller in diameter than the cylindrical opening 12 and therefore the plate extends inwardly beyond the wall of the cylindrical opening in the manner shown most clearly in Fig. 2. Located within the cylindrical opening is a piston 21. This piston has a central cavity 22 that extends from its upper end to a point near the lower end in a manner shown in Fig. 2. An elongated port 23 extends through the wall of the piston and communicates with the corresponding port 24 in the wall of the cylinder. The piston is provided with two or more piston ring grooves 25 near each end and located in these grooves are ordinary piston rings. The bottom of the piston is provided with a threaded opening 26 into which the upper end of the rod 27 is threaded in the manner indicated in Fig. 2. The rods or bolts 18 extend downwardly for a considerable distance and are connected near their lower ends by means of a plate 28 which is held in adjusted position by means of two pairs of nuts 29. By adjusting the nuts 29 the plate 28 can be moved towards or away from the plate 20. The piston rod 27 extends through an opening in the plate 28 and is surrounded by means of a helical spring 30. The upper end of this spring abuts the lower end of the piston, while the lower end rests on the upper surface of plate 28. The spring 30 is always under compression and tends to move the piston upwardly towards the top of the cylindrical opening and when there is no pressure acting on the piston, the latter will have its upper end in contact with the inner surface of the end wall 13. The spring is of such strength that when the pressure in the boiler attains the maximum value, it will move the piston downwardly to the position shown in Fig. 3 in which

position the ports 23 and 24 are brought out of alignment so that very little steam will pass through the pipes 9 and to the turbine. The parts are so adjusted, however, that sufficient steam will always flow to cause the turbine to 55

operate, but only at a very slow speed when the pressure has attained the maximum value. When the turbine slows down, the fan 8, which produces the air for the forced draft, will function 5 at a very slow rate with the result that the combustion will be very slow and therefore the steam will not be generated as fast as it is used and the pressure within the boiler will fall, thereby permitting the spring to move the piston upwardly so as to permit more steam to flow to the 10 turbine and increase the speed of the latter, whereby the draft will be increased and in this way the speed of the fan will be maintained at the proper value to secure the generation of the necessary amount of steam to maintain the pressure at the desired value. The pressure to be 15 maintained within the boiler can be adjusted by adjusting the tension of the spring 30, which can be done by moving the nuts 29 in the manner suggested. It will be observed that the piston is provided with two or more rings near each end and that the port 23 extends through the wall of the piston between the rings. The surface of the piston between the two innermost rings is 20 spaced a short distance from the surface of the cylinder so as to permit a small amount of steam to flow between the wall of the piston and the wall of the cylinder, thereby producing a balanced effect. Since it is not intended to cut off 25 the steam entirely from the turbine at any time, slight leakage due to the clearance between the piston and the cylinder can do no harm and therefore such clearance is provided so as to produce the balanced effect mentioned.

30 Attention is called to the fact that in this valve the piston performs two separate functions and serves both as a valve member to control the flow of the steam to the turbine and also as a pressure measuring device which determines the opening of the throttle valve.

35 The piston rod 27 is provided with a longitudinally extending groove 21. A spline cooperates with the groove for the purpose of preventing the piston and the piston rod from turning 40 in the cylinder and thus assures that the ports 23 and 24 will always be properly positioned so as to fully register with each other when the piston moves in the cylinder.

45 From the above description it will be seen that the pressure controlled valve that forms the subject of this invention is of a very simple and substantial construction and that it can be readily inserted in the steam line between a boiler and a steam turbine or other steam engine so as to 50 control the flow of steam in accordance with the pressure in the boiler.

55 In the embodiment illustrated, the area of the opening through the valve varies inversely with the steam pressure as this is necessary in order 60 to obtain the results desired. Although the valve has been described in connection with a forced draft steam generating plant, it can, of course, be employed in any place where the flow of fluid through a pipe is to be controlled in accordance with some variable pressure source.

65 Having described the invention what is claimed as new is:

1. A pressure controlled throttle valve, comprising, in combination, a body member having a cylindrical opening, one end of the opening being closed, a piston mounted for reciprocation in the opening and resilient means comprising a spring for urging the piston towards the closed end of the cylindrical opening, the space between the piston and the closed end of the cylindrical

opening forming a pressure chamber, the piston having an opening extending thereinto from the pressure chamber, and an opening extending through the wall of the piston and forming a port, the wall of the body member having a discharge port so located that it will be brought into register with the port in the piston at one position of its travel.

2. A pressure controlled throttle valve, comprising, in combination, a body member having a cylindrical opening, one end of the opening being closed, a piston mounted for reciprocation in the opening, resilient means comprising a spring for urging the piston towards the closed end of the cylindrical opening, the space between the piston and the closed end of the cylindrical opening forming a pressure chamber, the piston having an opening extending thereinto from the pressure chamber, and an opening extending through the wall of the piston and forming a port, the wall of the body member having a discharge port so located that it will be brought into register with the port in the piston at one position of its travel, and means for holding the piston from turning.

3. A pressure controlled throttle valve, comprising, in combination, a body member having a cylindrical opening, one end of the opening being closed, a piston mounted for reciprocation in the opening, resilient means comprising a spring for urging the piston towards the closed end of the cylindrical opening, the space between the piston and the closed end of the cylindrical opening forming a pressure chamber, the piston having an opening extending thereinto from the pressure chamber, and an opening extending through the wall of the piston and forming a port, the wall of the body member having a discharge port so located that it will be brought into register with the port in the piston at one position of its travel, and means for holding the piston from turning, and means for adjusting the tension of the spring.

4. A pressure controlled throttle valve, comprising, in combination, a body member having a cylindrical opening, one end of the opening being closed, a piston mounted for reciprocation in the opening, resilient means comprising a spring for urging the piston towards the closed end of the cylindrical opening, the space between the piston and the closed end of the cylindrical opening forming a pressure chamber, the piston having an opening extending thereinto from the pressure chamber and an opening extending through the wall of the piston and forming a port, the wall of the body member having a discharge port so located that it will be brought into register with the port in the piston at one position of its travel, and means for holding the piston from turning, and means for adjusting the tension of the spring.

5. A pressure controlled valve of the type described, comprising, in combination, a body member having a cylindrical opening extending inwardly from one end thereof, a piston slidably mounted in the cylindrical opening, the space between the end of the piston and the wall of the closed end of the opening forming a pressure chamber, a piston rod secured to one end of the piston, a guide for the piston rod, means for attaching the guide to the body member, a compression spring extending between the guide and the outer end of the piston for urging it towards the closed end of the cylindrical opening, the body member having a discharge port extending through its wall, the piston having an

opening extending from the end that is located in the cylindrical opening to the outside of the piston at a point between its ends, the opening in the piston wall being positioned to register with the discharge port in the body member at one point in the piston travel.

6. A pressure controlled valve of the type described, comprising, in combination, a body member having a cylindrical opening extending inwardly from one end thereof, a piston slidably mounted in the cylindrical opening, the space between the end of the piston and the wall of the closed end of the opening forming a pressure chamber, a piston rod secured to one end of the piston, a guide for the piston rod, means for attaching the guide to the body member, a compression spring extending between the guide and the outer end of the piston for urging it towards

the closed end of the cylindrical opening, the body member having a discharge port extending through its wall, the piston having an opening extending from the end that is located in the cylindrical opening to the outside of the piston at a point between its ends, the opening in the piston wall being positioned to register with the discharge port in the body member at one point in the piston travel, the opening in the wall of the piston being moved out of communication with the discharge port in the body member when the pressure in the pressure chamber exceeds a predetermined value.

7. A device in accordance with claim 1 in which there is a means for adjusting the force exerted on the piston by the spring.
